Attorney.

UNITED STATES PATENT OFFICE.

EDWARD W. BURT, OF BOSTON, MASSACHUSETTS.

BOTTOM-FILLER FOR WELT-SHOES.

1,180,004.

Specification of Letters Patent. Patented Apr. 18, 1916.

Application filed October 1, 1915. Serial No. 53,588.

To all whom it may concern:

Be it known that I, EDWARD W. BURT, a citizen of the United States, residing at Boston, in the county of Suffolk and State of Massachusetts, have invented new and useful Improvements in Bottom-Fillers for Welt-Shoes, of which the following is a specification.

My invention relates to bottom fillers for 10 welt shoes, and its objects are to eliminate fluidity of the filler, to prevent the formation of depressions and irregularities in the surface of the inner sole, to produce and preserve a uniform thickness of the filler 15 under all conditions of wear without spreading particularly at the ball of the foot, to obviate squeaking and creaking of the leather, to maintain the inner and outer soles in constant position relative to each 20 other while permitting great flexibility of the same, to make the sole of the shoe water and moisture proof, to inhibit deterioration of the filler through humidity and variations of temperature, to prevent cutting 25 away of the channel lip of the insole, to increase the duration of wear of the sole, to increase the therapeutic value of the shoe particularly in any shoe designed for the 30 cure of flat foot, to decrease the cost of manufacture, and in other ways to improve and render more useful and efficient the properties and arrangement of the various 35 parts of shoe bottoms.

In the manufacture of welted boots and 40 shoes in the United States, it is generally the custom, after the welt has been sewed to the insole, linings and upper, to introduce within the hollow space formed between inner edges of the welt seam inclosing 45 the outer face of the insole, a fluid filling compound substance known as the "bottom filler." Such filling is usually composed of ground cork, ground leather, and other powdered substances combined with 50 some well known adhesive such as rubber cement, glue or the like. It is ordinarily applied in the form of a soft paste to the face of the sole by means of a flat knife to secure a uniform surface flush with the 55 welt, and in order that it may be of the proper consistency for laying in the said hollow and at the same time dry rapidly, the filler is usually heated and softened before applying. Even when at its maximum dryness, however, the said filler after it has

been laid retains in a marked degree the property of fluidity, a condition which is increased by the heat and pressure of the human foot or exposure of the shoe to snow, water or dampness under the conditions of 60 daily wear. Because of the fluidity of such compound mixture, there is an irresistible tendency of the filler to flow along the lines of least resistance away from all points where pressure is exerted by the foot of 65 the wearer of the shoe, particularly the ball thereof, so that, in many instances the pressure of the ball of the foot upon the inner sole is so great, the filling substance will spread toward the toe and shank of the 70 shoe, packing into the part of the shoe where no pressure is exerted, and the inner sole will sink at the regions of pressure and cause indentations, breaks, ridges or pockets in and adjacent thereto. As a result, the 75 wearer of the shoe is occasioned great discomfort, and often sustains calli, flat foot, transverse arch trouble, or sores to such an extent as to render the shoe unwearable, or by the change of gait brought about by 80 such indentations, etc., to cause the shoe to quickly wear out. So general and serious is this defect where such form of filler is used, that it is common knowledge that shoe dealers are returning each year to the manufacturer thousands of pairs of shoes as imperfect in construction for this cause and are requiring the same to be replaced or credit given therefor. In some instances, 85 paper or similar substances are used as fillers, but are subject to the objections above set forth, being absorbent and compressible in character and subject to displacement in whole or in part upon the application of 90 continuous pressure particularly in the 95 presence of perspiration or moisture from whatever cause, or of the heat of the human foot.

After years of research and study, I have 100 invented a bottom filler which is free from the defects above described.

Primarily my invention consists of a flexible insert sole of non-compressible material, to each side of which is cemented a non-extensible waterproof fabric covering. 105

It also consists in other novel arrangements or combinations of materials and modifications illustrated in the drawing and hereinafter described and claimed.

Reference is hereby made to the drawing 110

in which similar numerals of designation refer to similar parts throughout the several views.

Figure 1 is a view of the bottom of a shoe upper which has been subjected to the operations of lasting and welting, and showing my bottom filler in position; Fig. 2 is a view in perspective of my improved insert; and Fig. 3 is a section of the upper shown in Fig. 1 after the outsole has been stitched to the welt.

Referring to the drawing: To each side of the insert sole 4 cut from a sheet of material which is substantially noncompressible by the weight of the human body and which is sufficiently flexible to bend easily, I secure the protective layers 5 and 6. The insert sole 4 is preferably of leatherboard or other solid substance which is non-yielding in character and at the same time is sufficiently pliable to admit of being bent in two different directions, as is required by the forepart of the shoe when in the act of walking.

By the term "non-compressible" as used in this specification, I desire to be understood as designating the property of the sole 4 to maintain constantly its uniform thickness and to resist compression, disintegration or separation or change of position brought about by the human foot under the conditions of pressure, temperature and wear to which shoes are constantly subjected.

Preferably the protective layers 5 and 6 are made of canvas or other fabric suitable for the purpose, and have part of their threads running longitudinally of the sole 4, and a part running laterally thereof in order to prevent any material extension of said layers either longitudinally or laterally. By such arrangement of threads, I guard against any possible tendency of the sole to be pulled out of shape in the directions specified, and against any likelihood of a consequent change in thickness. As is obvious, however, suitable materials other than fabric could be used for forming the said layers, and similar results could be secured.

By the words "longitudinally and laterally non-extensible" as used in connection with the protective layers 5 and 6, I refer to a property of such layers which is not necessarily confined to the use of fabric therefor or to the particular arrangement of the threads of any fabric employed for the purpose, but which is nevertheless present in whatever suitable material may be employed for the purpose.

For securing the protective layers to the sole 4, I employ any suitable adhesive, preferably one which is waterproof with great adhesive properties; for example, I find that good results can be obtained from a mixture

of shellac, rosin, gum mastic, oil paraffin, Manila gum chips, borax and wood alcohol, the sole being soaked in said compound when the compound is in a molten condition at a temperature considerably above that of the human body, and the protective layers being pressed thereon until the whole is saturated with the mixture, and firmly cemented together. The said mixture is preferably of the following formula, to wit,— 75 three quarts wood alcohol, two pounds Manila gum chips, one-half pound shellac, two pounds rosin, two pounds gum mastic, one ounce borax and one-quarter ounce paraffin oil. 80

In order to secure the best results, my improved bottom filler is shaped to cover the insole 7 and channel lip 8, and to extend as far as the rib formed by the welt seam 9. In applying the said filler, I first preferably 85 cement down the channel lip 8, and after again heating the filler to soften the compound with which it is impregnated, I firmly press the filler against the outer surface of the insole and adjacent parts above 90 designated. The outsole 10 is thereupon sewed to the welt 11, and the usual steps of shoe making completed, the operation of leveling serving to unite the outer faces of my bottom filler with all parts of the shoe 95 adjacent thereto.

By shaping the filler as above described, the edges of the same closely register with the between substance and trimmed edge of the upper adjacent to the welt seam, which fact taken in connection with the utilization of the fabric layers 5 and 6 and with the thorough cementing together of all the parts of the shoe bottom in proximity to the filler, renders any lateral displacement or rubbing of parts impossible, so that squeaking or creaking of the leather is entirely obviated. 100

By employing a waterproofing compound as above described the melting point of which is considerably above that of the human body, I prevent any deterioration of the filler through heat or dampness occasioned by the proximity of the human foot, and since I have completely guarded against lateral displacement of any part of the filler by pressure of the foot upon the insole there is no tendency for indentations, ridges or hollows to form beneath the ball or other parts of the sole of the foot, and all faulty construction in this respect is entirely removed. 110

As is obvious, various changes and modifications may be made in the construction of my improved device without departing from the spirit or purpose of my invention. 120

What I claim and desire to secure by Letters Patent is,—

1. A bottom filler for welt shoes, consisting of a flexible insert of non-compressible 130

material of substantial thickness, to each face of which is secured a sheet of material longitudinally and laterally non-extensible.

2. A bottom filler for welt shoes, consisting of a flexible insert of non-compressible material of substantial thickness, to each face of which is affixed a longitudinally and laterally non-extensible fabric, part of the threads of which run longitudinally thereof and part of which run laterally thereof, whereby said insert is made longitudinally and laterally non-extensible.

10 3. A bottom filler for welt shoes, consisting of a flexible insert of non-compressible material of substantial thickness, shaped to cover the insole and channel lip and to ex-

tend as far as the rib formed by the welt seam, to each face of which insert is secured a longitudinally and laterally non-extensible fabric, part of the threads of which run longitudinally thereof and part of which run laterally thereof, whereby said insert is made longitudinally and laterally non-extensible.

20 In testimony whereof I have hereunto set my hand in presence of two subscribing witnesses, this 30th day of September 1915.

EDWARD W. BURT.
